CONVERTING BULK FILAMENT INTO STAPLE FIBER

Kenneth L. Whitney, Claymont, Del., assignor to American Viscose Corporation, Philadelphia, Pa., a corporation of Delaware

Application April 14, 1955, Serial No. 501,345

20 Claims. (Cl. 19—6)

This invention relates to apparatus for converting bulk filament of continuous length such as rayon and nylon tows into a drafted continuous product of staple fiber ready for further drafting, testing, and other treatments suitable for converting the product into a yarn.

Equipment of the general nature described herein has been provided for the purpose of converting continuous filaments into staple fibers which are then shaped into a web or sheet of substantially parallel fibers and finally drafted to distribute the fibers into a random arrangement. The primary utility of such a machine is to avoid a substantial part of the carding, combing, gilling, and drafting operations conventionally performed in separate machines. In the prior art machines, however, drafting is ordinarily accomplished by nip rolls rotatable about fixed axes, and thus this rigid design adapts the machines for use with a very limited range of fiber lengths. When it is attempted, in such known machine, to draft staple fibers of a length more than 2 inches less than the distance between successive nipping rolls, fiber concentrations and unevenness result, thus providing an unsatisfactory product for yarn production. An undesirable product is also obtained when known equipment is used to process fibers of mixed lengths or "varied cut staple" in which the fibers may have a length greater or less than the optimum fiber length range for such equipment. Unsatisfactory operation of a conventional converter is further aggravated when the continuous filamentary material supplied thereto is crimped, because of the loss of efficiency of the drafting rolls resulting from the extensibility and resiliency of crimped fibers.

An object of the present invention is to provide apparatus constituted as a single machine for progressively converting a continuous supply of filamentary material into a continuous drafted staple product having better uniformity in texture and random fiber distribution and greater freedom from fiber concentrations than could be heretofore obtained.

Another object to provide apparatus which is adapted to convert filaments into staple fiber products having fibers of the same length and/or mixtures of different fiber lengths.

Still another object is to provide apparatus that is readily adjustable in order to carry out the foregoing object.

A further object is to provide apparatus, in accordance with the foregoing objects, capable of converting a supply material comprising crimped filaments, and particularly a supply material such as a plurality of heavy denier tows comprising crimped filaments.

A still further object is to provide apparatus, in accordance with the foregoing objects, capable of producing a crimped staple fiber product.

Other objects, features, and advantages will become apparent from the following description of the invention and the drawing relating thereto in which:

Fig. 9 is a fragmentary sectional view taken along line IX—IX of Fig. 8;

Fig. 10 is a fragmentary perspective view of crimping aprons shown in Fig. 1; and

Fig. 11 is a diagrammatic elevation of the driving system for the machine illustrated in Fig. 1.

Broadly speaking, the invention consists of apparatus for converting a running supply of continuous filaments into a drafted and uniformly textured bundle or sliver of staple filaments. The apparatus hereafter described is adapted to handle different lengths of staple, whether it be cut to uniform or mixed lengths. Although the invention is primarily concerned with an improved fiber drafting system, the apparatus as a whole contains other structural features which are believed to distinguish the invention from prior systems and which cooperate with the drafting system to produce a high quality staple fiber bundle.

The apparatus of the invention comprises, in a preferred embodiment, a preliminary filament stretching and sheet developing section; a section for cutting the sheet transversely into successive longitudinal portions; an adjustable driving system permitting changes of speed in fiber-advancing portions of the machine occurring after cutting to compensate for relaxation of the fiber before drafting; a section of improved design operating on the sheet portions to separate the fibers one from the other; and a drafting section comprising an upwardly-facing apron, a holding roll in nip relation with the apron and which is adjustable length-wise of the apron, a second or upper apron spaced from the holding roll and supported in adjacent relationship to an advanced portion of the first or lower apron and terminating therebeyond in nip relation with a traction roll. The upper apron and the traction roll are driven at a higher speed than the lower apron and the holding roll to shuffle the fibers, as they are released by the holding roll, to an extent which progressively increases from the bottom fibers to the top fibers of the web or sheet as it is carried on the lower apron. The apparatus further comprises a crimping section consisting primarily of a pair of converging aprons, driven at a slower linear speed than the traction roll and the upper apron, and a condensing section in which the crimped fibers are formed into a sliver or bundle of rotund cross-section.

With reference to the drawing for description of the invention in greater detail, Fig. 1 diagrammatically illustrates a filamentary material 5, ordinarily comprising a plurality of filament tows as it enters a preliminary tensioning section 6 comprising snubbing rolls 7 and drafting rolls 8. In passing between the snubbing rolls and the drafting rolls, the filaments may optionally be passed

around an additional pair of rolls 10 along any one of the three paths indicated in full and dotted lines. The rolls 10 may be reciprocated oppositely to one another in accordance with a conventional arrangement such as shown in Fig. 1b, to feed the filaments to a pair of cutting rolls 11 and 12 in a manner as to cause the rolls to cut the filaments to different staple lengths and/or to convert the tows or bundles of filaments into a sheet of filaments which has a relatively uniform crimp and thickness as it enters the nip of the cutting rolls. This first-mentioned result is obtained by reciprocating the rolls 10 through a relatively long stroke, at low frequency, lengthwise of their axes, while the second purpose is accomplished by a short frequent reciprocation of the rolls 10. The frequency and length of the reciprocating stroke of the rolls 10 may be so selected to dispose the filaments into a sheet having sinuous arrangement whereby the filaments are also cut to mixed lengths. A guide 14 is positioned along the path of sheet 5 between the rolls 11 and 12, constituting the cutting section, and the rolls 8 of the tensioning section. The guide 14 extends into close proximity to the nip of the cutting rolls and has lateral portions which engage the sheet edges to accurately restrict the sheet to a desired width before it enters the nip of the cutting rolls.

The rolls of the cutting section are of conventional type, wherein the roll 12 is a hard surface roll, known ordinarily as the "anvil" roll, while the periphery of the roll 11, known ordinarily as the cutting roll, comprises a helix formed of a hardened material, such as a hardened steel, which protrudes slightly above the cylindrical surface of a softer material, such as a resilient vulcanizate. Cutting is performed within the nip of the rolls 11 and 12 primarily by the crushing action of the helix against the fibrous filamentary material supported on the hard surface of the roll 12. The cutting of most filamentary materials, and particularly filaments comprising thermoplastic resins, tends to coalesce or adhesively join adjacent severed ends of staple fiber contained in the same strip or group thereof as produced by successive tracks of the helix upon the filament sheet. These tracks extend transversely of the filament sheet on a bias with respect to its length and thus form successive transversely extending strips as the sheet travels through the cutting rolls.

For best results, it is essential that crimped filaments be tensioned to dispose them in a substantially straight condition as they proceed into the nip of the cutting rolls. However, satisfactory cutting is not achieved if such filament tensioning is obtained by draft exerted by the cutting rolls, and thus the tension section 6 serves to impose the tension needed to extend or straighten the filamentary material supplied to the rolls 7. The peripheral speeds of the rolls 8 and the cutting rolls may then be adjusted so that a relatively small amount of tension is exerted on the filaments as they pass between the rolls 8 and the cutting rolls. Such treatment of the filaments results in cleaner cutting and staple fiber of higher quality.

Since the cutting rolls tend to coalesce adjacent fiber ends, it is necessary to separate each fiber at both ends, if possible, from its neighboring fibers. For this purpose a pair of debonding or fiber opening rolls 15 and 16 are provided. In certain conventional machines, rolls having longitudinally fluted surfaces which are loosely meshed together work the fiber in a fashion as to produce separation of the fiber ends. In the present invention, debonding rolls having intermeshing circumferentially-extending flutes are preferred, as shown in Figs. 7, 8, and 9. These debonding or fiber opening rolls 15 and 16 are formed with flutes which extend in accurate complementary, interdigital relationship. In order that the clearances therebetween may be accurately held to settings which most effectively promote debonding, means are provided for adjusting the axes of the rolls toward and away from each other while maintaining the same in parallel relationship. Thrust bearings are provided along the shafts of both debonding rolls to minimize end play

which is maintained below 0.005 inch. This structural arrangement is required in order that sufficient clearance between the flutes of the rolls may be maintained without severely pinching the fibers. However, the formation of the filament sheet within the tensioning section 6 provides uniform filament distribution which will, to a great extent, prevent non-uniform and severe fiber pinching between the debonding rolls. Rolls with circumferential flutes, such as rolls 15 and 16, are found to provide highly effective fiber separation as a result of the speed differences provided by the unequal diameters of the opposing corrugated surfaces of the intermeshing flutes.

10 The debonded fibers leaving the rolls 15 and 16 are then passed into a drafting section comprising a lower apron 18 carried by a plurality of driven rolls 19, 20, 21, and 22, and idler rolls 23 and 24. A pair of rolls 27 and 28 are supported above and are driven at the same peripheral speed as the apron 18. The apron 18 and rolls 27 and 28 together cooperate to advance the debonded fibers at the same linear speed at which they are moved through the debonding rolls.

15 The roll 27 is disposed directly above the roll 19 and is non-adjustable lengthwise of the path of the fibrous material, while the roll 28 is adjustable lengthwise of the path for reasons hereinafter explained. The apron 18 and the rolls 27 and 28 may be considered to be the snubbing portion of the drafting section.

20 The traction portion of the drafting section comprises an apron 30 carried by a pair of adjustable idler rolls 31 and 32 and a driven roll 33. The apron 30, and its supporting rolls, are disposed above the fiber path with the lower reach of the apron 30 extending from the roll 32 to the roll 33 in superjacent relation with a driven roll 34 and the upper reach of the apron 18. The rolls 33 and 34 are disposed in nip relationship with the roll 34 being driven at a speed common to the peripheral speed of the apron 30. An important feature of this invention is that the traction portion is driven at a considerably higher speed than the snubbing portion of the drafting section. The length of the apron 30 disposed above the apron 18 and the angle of inclination of its lower reach are adjustable, and in this manner the drafting of the fiber may be controlled to an almost infinite degree. A satisfactory speed ratio of the traction portion to the snubbing portions is 10 to 1, although this ratio may be varied as desired to suit a large variety of conditions.

25 The inclination and length of the lower reach of the apron 30 is varied by adjustment of the idler rolls 31 and 32 relative to slots 35 and 36 formed in support plates 37 and 38, respectively. Similar supporting plates are provided on opposite sides of the machine for supporting each of the rolls 31 and 32 at both ends thereof. Other adjustments of the apron 30, by changing the positions of the rolls 31 and 32 and the plates 37 and 38, are illustrated in Figs. 3 and 4. These figures also illustrate different positions of the roll 28, which are correlated with adjustment of the apron 30 to handle different lengths of staple fiber. For example, in Fig. 1 the wide spacing between the roll 28 and the apron 30, taken with the relatively long length of the lower reach of the apron 30, adapts the apparatus for processing fibers of long length, while Figs. 3 and 4 illustrate the machine adjusted for handling fibers of shorter lengths wherein the roll 28 is positioned closer to the apron 30, which itself is provided with a lower reach of reduced length.

30 As a result of the difference in surface speeds of opposing sections of the aprons 18 and 30, the uppermost fibers of the web carried by the upper reach of the apron 18 are advanced at the fastest rate by the apron 30 as soon as the web is released from the nip formed by the roll 28 and the apron 18. The fibers within the web are thus advanced progressively more rapidly in accordance with their height within the web. In view of the inclination of the lower reach of the apron 30, the nip formed by the aprons gradually becomes more effective, as the

web of fibers advances therebetween in shifting the fibers relative to each other, with its maximum effect being exerted as the web passes out from between opposing portions of the aprons and into the positive nip provided by the apron 30 and the roll 34.

The drafted fiber is discharged from the traction portion of the drafting section as a sheet of fibers which moves into a crimping section comprising two opposed aprons 40 and 41. These aprons have mutually facing reaches which define the path of the staple fibers as they are advanced into a condensing section 42. The aprons 40 and 41 are supported so as to provide a gradually narrowing region 45 defined by the opposing converging reaches of the aprons. The aprons 40 and 41 are driven at substantially slower speeds than the traction portion of the drafting section by driven rolls 43 and 44 so as to gather or compress the sheet of staple fiber lengthwise into plaits as it issues from the drafting section and enters the enlarged end of the region 45. The plaits are compressed as they are carried by the aprons into progressively narrowing portions of the region 45, and issue from the nip of these aprons in a packed or highly crimped state. This treatment of the fiber sheet tends to restore all the crimp originally possessed by the filament and serves also to promote further crimping.

The apron 40 normally has a fixed path with an idler roll 47 being provided to maintain it in a taut condition. The support for the apron 40 comprises, in addition to the roll 44, a frame 48 which supports a small idler roll 49, and forms a guide portion 48a over which the upper reach of the apron 40 slides during the fiber crimping action.

The apron 41 is supported by the driver roll 43, an idler roll 51 which is urged against the inner surface of the apron by springs 52, and a second idler roll 53. These rolls are rotatably carried by a frame 55 which also provides a seat for the springs 52 and forms a guide portion 55a over which the lower reach of the apron 41 rides. The axes of rolls 43 and 53 are fixed with respect to the frame 55, however, the frame itself is pivotally supported in slotted bearing members 58 located at opposite sides of the machine. These bearing members each have a slot 59 for receiving an extension of the shaft 61 of the roll 43 and are supported for vertical reciprocation by guides or supports 60. Spring 62, supported between the member 58 and a set screw 62a of the stationary bracket 62c, resiliently urges the bearing 58 downwardly, and thus the assembly for apron 41 may, in effect, move lengthwise of the path for the fiber. Movement in this direction is necessary in order that this assembly may move forward to allow the apron 41 to clear the apron 30 whenever the end of the assembly, as defined by the roll 53, needs to tip upward. With this adjustment of the apron assembly, the lower reach of the apron 41, of course, increases its inclination to the lower apron 40 without necessarily changing the spacing between the rolls 43 and 44.

The tipping motion of the apron assembly, as described above, is resiliently controlled by a pair of rods 63 which extend from the frame 55, outwardly of the apron 41, to stationary adjustable brackets 64 through which they are longitudinally slidable. The frame 55 is resiliently held in a desired position by springs 66 and 67 which encircle the rods and engage with a swivel element 64a, carried by the bracket 64, and stops 68 and 69 fixed to the opposite ends of the rods 63. In order that the normal position of tilt of the apron 41 may be changed, each bracket 64 is slotted in a direction parallel to the axis of the rods 63 whereby the entire apron assembly may be moved to change the angle of inclination of the lower reach of the apron 41.

The crimped, fibrous sheet is ultimately discharged into the condensing section 42 comprising a flume 71 having opposite rolled edges 72 and a cover portion 73. As the fibrous sheet progresses lengthwise of the flume, the edges

thereof are rolled over and the sheet as a whole is gathered into a narrow cross-section as it issues from the end of the flume and proceeds into a curved funnel-like condenser 75. This condenser 75 reduces the product to a still smaller cross-section so that the fibrous bundle may easily enter the nip formed by a pair of overlapping condensing rolls 77 and 78. The roll 77 comprises a center section 79 of smaller diameter than its end sections 81 and 82, while the roll 78 fits between the two sections 81 and 82 of the roll 77. Normally the roll 77 is driven, while the roll 78 is free to rotate as a result of its frictional contact with the fibrous bundle drawn between these rolls. Springs 83 and 84 are positioned in slots formed in the frame members 88 and 89 and bear against the ends of the shaft carrying the roll 78 to urge the same toward the roll 77. The condensing rolls serve to propel the fibrous bundle through the condensing flume 71 and the condenser 75, as a highly condensed bundle which is received by a conventional coiler 86 comprising a rotatable top 87.

Fig. 11 diagrammatically illustrates a system for driving the apparatus described hereinabove. The gears or sprockets which are coaxial and rotatable with a roll hereinbefore named have the same numeral with the letter "a" added. The letter "b" is added in those instances where there is a second gear or sprocket coaxial with a roll. The prime mover for the system is a motor 90 connected by a sprocket drive 91 to a main drive shaft 92. The drive shaft is connected with the snubbing rolls 7 of the tensioning section by a variable drive unit 93 and a sprocket drive which connects the unit 93 with one of the shafts of the snubbing rolls supporting one of the intermeshing gears 7a. As the cutting section may be driven in fixed ratio with the traction rolls 8 of the tensioning section, the intermeshing gears 8a of the rolls 8 are connected in direct driving relation with gears 11a and 12a for driving the rolls 11 and 12. The gears 11a and 12a intermesh and one of these gears, namely, 12a, is connected by a sprocket drive to a bevel gear unit 94 driven by the shaft 92. The debonding rolls 15 and 16 are driven at approximately the same speed as the snubbing portion of the drafting section and thus may be connected in direct drive relationship with rolls 19 and 27. Hence, the gears for driving these rolls are connected in series relationship extending through the snubbing portion to the traction portion of the drafting system. The gears for driving the traction rolls 33 and 34 are 33a and 34a respectively. The gear 34a is connected by gear 97 and a pair of speed reduction gears 95 and 96 to gear 22b in coaxial relation, and turning with the roll 22 and a gear 22a. The roll 34 is primarily driven by a sprocket drive from a variable speed unit 98, thus the debonding section and the entire drafting section of the converting machine are driven from the variable speed unit 98. Another variable speed unit 99 is connected by a sprocket drive to a sprocket 44b coaxial with the roll 44, the shaft of which requires a coaxial gear 44a meshed with the gear 43a of the roll 43. Another sprocket 44c is connected by chain with a sprocket 77a for driving the condensing rolls 77 and 78.

Adjustment of the roll 28 backward or forward along the path of the fibers may make necessary the adjustment of the sprocket drive system therefor. As shown in Fig. 11, a sprocket chain 149 extends around a sprocket 28a mounted integrally and coaxially on the roll 28, a sprocket 146 which is attached coaxially with a gear which interconnects gears 20a and 21a mounted integrally with rolls 20 and 21, an adjustable idler sprocket 147, and a sprocket 148 which is attached coaxially with a gear interconnecting gears 21a and 22a of corresponding rolls 21 and 22.

It will be noted that all of the rolls of the converter that are disposed beyond the tensioning section 6 and

above the path of the fibers are spring-loaded in such a direction as to urge the rolls resiliently against the fibers, and the bearings for these rolls are arranged for movement in a vertical direction. Provision is made in the guides for such bearings that the rolls may undergo vertical movement within a range of a few hundredths of an inch. Normally the range of movement does not exceed about two hundredths of an inch. Notwithstanding this movement of the rolls toward and away from the lower rolls of the path of the fibrous material, construction of a drive system primarily from gears in parallel arrangement is preferable in order to eliminate the backlash or slackness that results from drive systems which are based essentially upon chain or belt drives. Although sprocket drives are employed in the driving system illustrated in Fig. 11 they are used primarily for connecting the separate functional systems or sections of the apparatus in relatively parallel arrangement from the main shaft 92. Thus, the use thereof does not result in accumulated slack or backlash such as might result if the rolls were generally interconnected by sprocket drives, and especially a series of sprocket drives.

Figs. 5 and 6 are detailed views of the traction portion of the strand-drafting system illustrated in Fig. 1. As shown, rolls 31, 32, and 33 support the apron 30. The roll 33 is urged resiliently toward the roll 34 to produce tight engagement of the apron 30 with the roll 34. Pressure on the roll 33 is obtained within two bearing assemblies located at opposite ends of the roll shaft. One of such bearing assemblies is shown in Figs. 5 and 6 and comprises springs 105 and 106 supported in a compressed condition between plungers 107 and 108, which are adapted for lengthwise movement within a guide portion 110 of a bearing frame 112, and a pressure plate 113 held against the springs by a set screw 114 threaded through the frame top portion 115. The shaft 33d of the roll 33 extends through and is rotatable relative to a bearing block 117 which is slidably disposed between the spaced parallel side walls of the frame 112.

A bearing structure and supporting frame corresponding to that just described above is, of course, provided on the opposite side of the machine to receive a portion of the shaft extending beyond the opposite surface end of the roll 33. The rolls 11, 15, 27, and 28 are all resiliently urged downwardly toward the path of the fibers, as illustrated in Fig. 1, and are mounted in bearing assemblies similar to that just described for roll 33.

The rolls 31 and 32 are provided for adjusting the length and inclination of the lower reach of the apron 30 to vary the degree of contact between the apron 30 and the fibers which are advanced from the nip of the roll 28 and the apron 18. The rolls 31 and 32 have identical bearing systems at the opposite ends thereof which are adjustable relative to their respective supporting brackets 37 and 38.

Referring now to Fig. 6 for a more detailed illustration of one of such bearings, the shaft 31c of the roll 31 passes through a sleeve bearing 118 which extends through a slot 35 in the supporting bracket or plate 37. The exterior surface of the bearing 118 is threaded to receive a nut 119 and also has a pair of shoulders 121, 122 (Figs. 5 and 6) which are sufficiently narrow to pass through the slot 35, but bear up against the plate 37 when rotated through 90 degrees, as shown best in Fig. 5. When the nut 119 is tightened against a washer 123, which engages the outer surface of the support plate 37 along both sides of the slot 35, the position of the bearing assembly relative to the plate is fixed. The rolls 31 and 32 have preferably a diameter smaller than the width of respective slots 35 and 36 so that an entire assembly comprising a roll and its bearing assemblies may be removed simply by loosening the nuts 119 at both ends of the roll, rotating the bearings 118

5 to their shoulders with the support plate slots, and then transferring the roll endwise through the slot of the support plate 37. Adjustment of the rolls 31 and 32 along their respective support plate slots may be accomplished without removing the rolls from their supporting plates by simply unloosening the nuts of the respective bearing assemblies.

The machine illustrated in Fig. 1 comprises a frame member running lengthwise of the machine along each side of the path transversed by the filaments and staple fibers. One of these frame members 125 is shown in Fig. 6 and includes two longitudinally extending portions 126 and 127. The frame portion 127 may be suitably bored as shown in Fig. 5 to journal the trunnions or stub shafts of rolls 20, 21, 22, and 24. In a similar manner, the stub shafts of rolls 16 and 19 (not shown) are journaled in the frame member 127. The upper frame portion 126 is secured to the frame portion 127 by a plurality of cap screws 128 and provides a section which overhangs the frame portion 127. This overhanging section is longitudinally slotted to receive bolts 130 which extend through toe portions of the support plates 37 and 38. The slot 131 for the bolts extends between dotted lines 132 and 133 shown in Fig. 5, and thus the support plates 37 and 38 are adjustable at opposite sides of the machine to provide desired adjustments of the apron 30.

Whenever the length of the lower reach of the apron 30 is changed, the longitudinal position of the roll 28 may need also to be altered. Such changes are made when it is desired to adapt the machine for handling a different length and type of staple fiber than previously processed in the machine. To permit adjustability of the roll 28 lengthwise of frame members 125, a bearing housing 135, and its mating bearing housing at the other side of the machine, are each provided with toes 136. Bolts 138 and 139 extend through the toes 136 and are received in a slot 141 formed in the frame portion 126. The lower face of the slot 141 is enlarged to provide space for the bolt heads and to form longitudinal shoulders with which the bolt heads engage when the nuts thereof are tightened. By loosening the bolts, the opposite housings for the roll 28 may be shifted lengthwise of the frame members 125. Since it is not necessary to change the position of the roll 33 lengthwise of the machine, the bearing housings 112 therefor may be fixed to the parallel frame members 125 of the machine by bolts 144, extending laterally of the housing 112, and a bolt 145 extending through a toe overhanging the slot 141.

While a preferred embodiment of the invention has been shown and described, it is to be understood that changes and variations may be made without departing from the spirit and scope of the invention as defined in the appended claims.

I claim:

1. Apparatus for converting a continuous running sheet of longitudinally oriented filaments into a continuous product of drafted staple fibers comprising means for severing the sheet of filaments into successive strips of staple fibers, means for opening the cut strips of fibers and discharging the same as a sheet, a first apron, means supporting said apron with a surface thereof extending along a path leading away from the opening means, first movable means positioned adjacent to said opening means and in nip relationship with said surface, second movable means positioned adjacent to the path and beyond the end of said apron furthest from the opening means, a second apron, means for supporting said second apron opposite the path with a surface thereof in nip relationship with said second movable means, said last-mentioned surface having a portion thereof disposed opposite said first-mentioned surface, third movable means, means for supporting said third movable means in nip relationship with the first-mentioned surface at a position between the second apron and the first movable means, and means for driving said second apron and second movable means at

a faster speed than said first apron and first and third movable means.

2. Apparatus for drafting a continuous sheet of staple fibers comprising two endless aprons, one disposed above the other, means for driving the two aprons with the upper apron moving at a substantially greater speed than the lower apron, means in nip relation with the trailing portion of the upper reach of the lower apron for positively gripping the sheet of fibers and advancing the same between the two aprons at the speed of the lower apron, and means in cooperative relation with the upper apron for advancing the sheet of drafted fibers discharged from between the two aprons, the upper apron and said last-mentioned means arranged to positively grip the fibers and advance the same at the speed of the upper apron.

3. Apparatus for converting a continuous running sheet of longitudinally oriented filaments into a continuous product of drafted staple fibers comprising means for severing the sheet of filaments into successive strips of staple fibers, means for opening the fibers and discharging the same as a sheet, a lower apron, means for supporting the apron with an upwardly-facing section thereof extending along a path leading away from the opening means, a first roll positioned in nip relation with a portion of said apron section nearest the opening means, a second roll disposed adjacent to the path and beyond the end of said apron furthest from the opening means, a second apron, means for supporting said second apron above the path with a downwardly-facing section in nip relation with the second roll, said second apron extending rearwardly over a portion of the first apron, a third roll, means for supporting said third roll in nip relation with the upwardly facing section of the first apron at a position between the second apron and the first roll, and means for driving said severing means, opening means, rolls, and aprons in synchronous relationship, with the second apron and the second roll being driven at a faster speed than the first apron and the first and third rolls.

4. Apparatus as defined in claim 3 wherein the means for supporting the third roll is adjustable lengthwise of the path between said second apron and the first roll.

5. Apparatus as defined in claim 3 wherein the means for supporting the second apron comprises at least one idler roll for supporting the rearward end of said downwardly facing section, and further including means for adjusting the idler roll toward and away from said first apron.

6. Apparatus as defined in claim 4 wherein the supporting means for the second apron comprises at least a pair of spaced idler rolls adjustable along separate ambits extending toward and away from the first apron.

7. Apparatus as defined in claim 6 comprising separate means for supporting each idler roll, said idler roll supporting means being adjustable in a direction lengthwise of the path.

8. Apparatus as defined in claim 3 wherein said means for opening the fibers comprises a pair of intermeshing grooved rolls.

9. Apparatus as defined in claim 3 wherein the opening means comprises a pair of rolls, each having circumferentially extending grooves and ridges extending in complementary meshing relation with the grooves and ridges of the other roll, the axes of rotation of said meshing rolls being spaced to provide substantially close uniform clearance between adjacent roll surfaces.

10. Apparatus as defined in claim 3 wherein said driving means comprises a primary drive means and separate means for independently connecting the primary drive means with the cutting means; and an assembly comprising the first and second aprons, and the first, second, and third rolls; and the opening means, one of said separate means comprising a variable drive unit for altering the speed of the cutting means with respect to that of said assembly.

11. Apparatus as defined in claim 3 wherein said sup-

porting means for the second apron comprises a relatively large roll disposed in nip relation with said second roll and connected with said driving means, and further wherein all of said rolls of the apparatus connected with the driving means and disposed above said path having means associated therewith for resiliently urging the rolls toward the path.

12. Apparatus as defined in claim 3 wherein the third roll is spaced rearwardly from the second apron a distance greater than the length of said staple fiber, and wherein said second roll is spaced from the first apron a distance less than said length of the staple fiber.

13. Apparatus for converting a sheet of longitudinally oriented filaments into a continuous product of drafted crimped staple fibers comprising means for severing the sheet of filaments into successive strips of staple fibers, means for opening the fibers and discharging the same as a sheet, a lower apron, means for supporting the apron with an upwardly-facing section thereof extending along a path leading away from the opening means, a first roll positioned in nip relation with a portion of said apron section nearest the opening means, a second roll disposed adjacent to the path and beyond the end of said apron furthest from the opening means, a second apron, means for supporting said second apron with a downwardly-facing section in nip relation with the second roll, said second apron extending rearwardly over a portion of the first apron, a third roll, means supporting said third roll in nip relation with the upwardly-facing section of the first apron for adjustable movement lengthwise of the path between the second apron and the first roll, means for crimping fibers discharged from the nip of the second apron and the second roll, and means for driving said severing means, opening means, crimping means, rolls, and aprons in synchronous relationship, with the second apron and the second roll being driven at a faster speed than the first apron and the first and third rolls.

14. Apparatus as defined in claim 13 wherein the crimping means comprises a lower apron having an upwardly-facing section coinciding with said path, an upper apron having a downwardly-facing section disposed above said path, rolls having fixed axes supporting the lower apron of said crimping means, and adjustable resiliently mounted means for supporting the upper apron of said crimping means.

15. Apparatus as defined in claim 13 wherein said driving means comprises a primary driving means and independent connections thereof with the cutting means; the opening means; the first and second aprons, and the first, second, and third rolls; and the crimping means, the driving connections for said opening and crimping means each including a variable drive unit for independently varying the speeds of fiber advancement of said opening and crimping means with respect to the cutting means.

16. Apparatus as defined in claim 13 wherein said supporting means for said second apron comprises a relatively large roll disposed in nip relation with said second roll and connected with the driving means, and further wherein all of said rolls of the apparatus connected with the driving means and disposed above said path having means associated therewith for resiliently urging the rolls toward the path.

17. Apparatus for converting a plurality of filamentary tows into a continuous product of drafted staple fibers comprising a tensioning section including a plurality of snubbing rolls in nip relationship, a plurality of drafting rolls in nip relationship and spaced from the snubbing rolls, at least one reciprocable roll disposed between said snubbing and drafting rolls in spaced relation therewith, means for reciprocating said last-mentioned roll lengthwise of its axis, all of said rolls of the tensioning section having axes of rotation substantially parallel; means for severing the filamentary tows discharged by the tensioning section into successive strips of staple

fibers; means for opening the fibers and discharging the same as a sheet; a lower apron, means for supporting the apron with an upwardly-facing section extending along a path leading away from the opening means; a roll positioned in nip relation to a portion of said apron section nearest the opening means; a second roll disposed adjacent to the path and beyond the end of said apron furthest from the opening means; a second apron, means for supporting said second apron above the path with a downwardly-facing section in nip relation with the second roll, said second apron extending rearwardly over a portion of the first apron; a third roll, means for adjustably supporting said third roll in nip relation with the upwardly-facing section of the first apron within a range extending lengthwise of the path between the second apron and the first roll; and means for driving the tensioning section, opening means, rolls, and aprons in synchronous relationship, with the second apron and the second roll being driven at a faster speed than the first and third rolls, and with said drafting rolls having a higher peripheral speed than the snubbing rolls.

18. A method of drafting staple fibers comprising disposing the fibers as a continuous web of substantially uniform width and thickness, advancing the web upon a flat running surface, snubbing the web against draft applied thereto by continuously engaging the upper surface of the web at the same speed as that of the running surface at a fixed position thereover to positively grip the web, engaging the upper surface of the web continuously along a path which is disposed above said running surface and extends from a point spaced forwardly of said snubbing position to a point beyond end of said running surface, drafting the fibers of the web by moving the upper surface thereof along said path at a speed greater than that of said running surface, positively gripping the drafted fibers as they leave said running surface and advancing the same at the speed at which the upper surface of the web is moved along said path during the drafting thereof.

19. A method of drafting staple fibers comprising disposing the fibers as a continuous web of substantially uniform width and thickness, advancing the web upon a flat running surface, snubbing the web against draft applied thereto by continuously engaging the upper surface of the web at the same speed as the running surface at a fixed position thereover to positively grip the web, continuously engaging the upper surface of the web along a path disposed above and inclined toward said running surface in the direction of fiber advancement, drafting the fibers of the web by moving the upper surface thereof at a speed greater than said running surface, and engaging said web at a location spaced from said snubbing position a distance at least equal to the length of the staple fibers.

20. A method of drafting staple fibers comprising disposing the fibers as a continuous web of substantially uniform width and thickness, advancing the web upon a flat running surface, snubbing the web against draft applied thereto by continuously engaging the web face opposite said running surface at the same speed as the running surface at a fixed position to positively grip the web, continuously engaging said web face along a path extending from a point spaced forwardly of said snubbing position to a point beyond the end of said running surface, and drafting the fibers of the web by moving said web face at a speed greater than that of said running surface.
